UNITED STATES PATENT OFFICE.

WALTER CHIPPERFIELD, OF HORNCURCH, ENGLAND, ASSIGNOR TO A. B. DICK COMPANY, OF CHICAGO, ILLINOIS, A CORPORATION OF ILLINOIS.

TYPE-COMPOSING MACHINE.

1,369,914.

Specification of Letters Patent. Patented Mar. 1, 1921.

Application filed January 27, 1920. Serial No. 354,358.

To all whom it may concern:

Be it known that I, WALTER CHIPPERFIELD, a subject of the King of Great Britain, residing at Kinkora, Great Nelmes, Hornchurch, Essex, England, have invented certain new and useful Improvements in Type-Composing Machines, of which the following is a specification.

My invention relates to a machine in which a type font is employed, comprising a frame about which a plurality of type troughs are arranged, in which the various desired types are contained. In accordance with the present invention a detachable composing stick is carried by a mechanism which is so arranged that the manual operation of selective devices such as the keys of a keyboard mechanism will serve to align the composing stick with any desired one of the type troughs. When the composing stick is thus aligned another manually operated mechanism is brought into play, such as one comprising a presser bar and mechanism operated thereby, which results in the bottom type contained in the selected type trough, falling into the composing stick. When the composing stick has been filled with the various selected types, the same is removed from its carrying mechanism and an empty composing stick substituted.

In the operation of mechanism of the character referred to it is necessary that the bottom type in each type trough normally be retained in position, and that the retaining means for the bottom type of any type trough be removed from operative position and the next uppermost type be retained in position when the bottom type is to be allowed to pass into the composing stick from the type trough which is in alignment with the composing stick at any moment. Appropriate mechanism of this character is provided by my invention. Preferably a pair of levers are mounted on or adjacent to each type trough. When the composing stick has been aligned with any type trough a lever, in the preferred form of my invention, is carried by the frame which carries the composing stick, into position to operate the levers which appertain to the particular type trough. The operation of a presser bar or other manual means is then caused to operate the lever which has been adjusted

with the composing stick, the operation of this lever serving to operate one of the type trough levers to release the bottom type and to operate the other lever to grip the next uppermost type.

My invention consists in improved mechanisms and combinations of parts of the character above referred to.

In order that my invention may be more fully understood attention is hereby directed to the accompanying drawings forming part of this application and illustrating one form of my invention. In the drawings Figure 1 represents partly in side elevation and partly in section, so much of a manually operated type composing machine, embodying my invention, as will be necessary for the purpose of this specification; Fig. 2 is an enlarged view partly in side elevation and partly in section of the part of the mechanism by which the delivery of the type from the type storage troughs is controlled; Fig. 3 is an enlarged horizontal section showing one of the type storage troughs with the type in position; Fig. 4 is a similar section taken through the composing stick and Fig. 5 is a view similar to Fig. 2 but showing a modified construction of the mechanism there illustrated.

Referring more particularly to Figs. 1 to 4 of the drawings, the machine comprises a base plate 1 from which any convenient number of standards 2 proceed to support a font 3 at a convenient distance above the base plate 1. The font 3 comprises a frame 4 of any suitable construction and which in this case is conical, around the periphery of which are carried a number of type troughs 5, which troughs in horizontal section may be of the construction shown at Fig. 3, and within each of these troughs is a store of type, such as the type shown at 6, Fig. 3, which are prevented leaving the base of the troughs and the delivery of which therefrom is controlled by mechanism hereafter described.

A composing stick 7, Fig. 1, of a suitable character is employed, that is, the composing stick is formed with a lengthwise extending dovetail channel such as is shown in the horizontal enlarged section of the composing stick at Fig. 4, and is adapted to receive type 6 from any one of the storage

troughs 5. Such a composing stick 7 is carried from a vertical revoluble shaft 8 by a radial frame 9 in an inclined position corresponding to the inclination of the troughs 5, 5 so that the upper receiving end of the composing stick 7 can be traveled by the angular motion of the shaft 8 below the lower ends of the series of type-containing troughs mounted upon the periphery of the station- 10 ary type font 3.

Mechanism is provided whereby when the composing stick 7 has been angularly moved to position beneath the desired type trough 5 of the font 3, the operator by the operation 15 of a presser bar or the like, can actuate mechanism connected with that particular trough of the font, by which the type next above the lowermost type is held in position, while the lowermost type is simultaneously 20 released and allowed to fall into the trough of the composing stick.

In order to operate the shaft 8 carrying the composing stick 7, the said shaft is near its lower end fitted with a gear wheel 10, 25 gearing into the teeth of a segmental rack 11 carried from a lower horizontal shaft 12, which segmental rack 11 may be formed with a disk 13 concentric with the said horizontal shaft 12 and free to revolve thereon.

30 It will now be understood that if a definite angular rotary movement is given to the disk 13 with its segmental rack 11, a proportional angular rotary movement will be given to the radial frame 14 fixed on the 35 vertical shaft 8 and to the composing stick 7 carried thereby, which will bring the upper end of the latter beneath a particular trough 5 of the type font 3.

In order to enable the composing stick 7 40 to be mechanically brought beneath a trough 5 of the font 3 containing the particular letter or figure required, the machine is shown as fitted with mechanism of the following character.

45 Upon the horizontal shaft 12 which is carried from the bed plate 1 of the machine and which freely supports the segmental rack 11 and disk 13 aforesaid, there are also freely and independently mounted two 50 platforms 15, 16, one extending upon one side of the shaft 12 and the other upon the opposite side, said platforms 15, 16 being supported in their normal positions as shown, by counterweights, springs or the 55 like against suitable stops, not necessary to illustrate in the drawings, and it will therefore be sufficient, since the platforms 15, 16, and their coating parts are similar, to describe one of the platforms and its parts.

60 The platform 15, carries a two-armed pawl lever 17, one arm, the lower arm for instance, having a tooth which by the rocking of the pawl lever 17 can enter a notch 65 18 in the edge of the disk 13 carrying the toothed segment 11, but when the platform

is in its normal and inactive position an arm of the pawl lever 17 contacts with a stationary stop indicated at 19 which holds the pawl lever 17 away from engagement with the disk 13; when however the platform is depressed the pawl lever 17 is taken away from the stop 19 and immediately becomes engaged by spring action with the disk 13 and consequently any further downward movement of the platform 15 will 75 rock the disk 13 on its axis and give an angular rotary movement of adjustment to the radial frame 14 and to the composing stick 7 in accordance with the distance through which the platform 15 is rocked. 80 The mechanism is arranged so that one of the platforms is adapted to move the composing stick 7 through an arc of travel up to 180°, while the opposite platform can give the composing stick an arc of travel 85 up to 180° around the opposite side of the font.

In order to operate the platforms 15, 16, that is to rock one or other of them through the required distance to bring the composing stick 7 under any particular type trough 5 of the font, the following means may be adopted: A stationary frame 20 is shown at Fig. 1 carried from the base plate 1 and located above the platforms 15, 16, and this 95 frame 20 carries two sets of type keys 21 and 22, one set 21 acting on the platform 15 and the other set 22 upon the other platform 16, each key representing a letter or figure, and each key corresponding in fact 100 to a trough of the type font. Each key is constructed with a head such as 23 upon which the operator presses, and the head 23 is carried upon a vertical stem slidable in a guide in the stationary frame 20, and the 105 distance through which each key can be depressed is definitely limited (as by collars 24 for instance), the distance of travel possible for one key varying from the distance of travel of another key, and so on. 110

The lower ends of the stems of the keys, considering one set, rest upon that platform which is immediately below that set of keys. By this arrangement, when a key is depressed through its limit distance it will 115 depress the platform and rock the latter about the horizontal shaft 12 through a definite angle, and consequently the disk 13 carrying the segmental rack 11 will likewise be moved through a definite rotary angle, 120 and the gearing 10, 11 is so proportioned that the composing stick 7 will be carried around to beneath the lower end of a trough 5 of the composing font 3 containing the letter or figure which corresponds with 125 that to which the particular key depressed is allocated.

The lowermost type of the particular trough 5 beneath which the composing stick 7 thus becomes located is released by means 130

hereafter described, actuated by the operator, and the type so released passes into the composing stick 7, and upon the operator removing pressure from the key operated, the platform will immediately assume its normal position by any conveniently arranged springs or balance weights (not shown) as also will the composing stick 7, and the machine is in a position for 10 the operation of the next key, and so on.

The mechanism according to this invention for effecting the release of the lowermost type of a font trough 5 and the retaining therein of the type above the lowermost type, in order to permit the lowermost type to pass from the font trough 5 to the composing stick 7, and at the same time to insure that the composing stick shall register with the particular font trough 5 15 and shall be maintained in that position during the passage of the lowermost type from the font trough to the composing stick, will now be described with particular reference to Figs. 1 and 2.

25 For each trough 5 of the font the conical structure 4 carries a two-armed lever 25, termed the first lever which is pivoted at 26 to the framework 4 of the font; one arm of the first lever 25 carries a tooth 27 which 30 extends below the lower end of the trough 5 and normally prevents the lowermost type leaving the same.

Pivoted to the said toothed arm of the first lever 25 is a second single-armed lever 35 35 which has a projection 29 opposite to the base of that type immediately above the lowermost type, and the second lever 28 extends toward the axis of the font and has a curved end; a spring 30 connects that arm 40 of the first lever 25 not provided with a tooth, with the second lever 28, and the arm of the second lever 28 normally rests against a stop 31 on the font which prevents the second lever 28 being rocked by the spring 45 toward the arm of the first lever 25, and consequently the tooth 27 of the first lever 25 is at the same time held beneath the trough 5 by the said spring. It will be understood that both the levers 25 and 28 mentioned are carried by the font which is stationary.

The vertical revoluble shaft 8 coaxial with the axis of the font is provided, as previously described, with a carrier comprising the radial frame 14 into which the composing stick 7 can be quickly inserted so that it is in line with the troughs 5 of the font, and as before explained this vertical shaft 8 is revoluble by means such as have 55 been described.

60 The radial frame 14 carried by the vertical shaft 8 supports a two-armed lever 32, one arm of which engages a sliding collar 33 on the vertical shaft 8, which collar 33 is operated, preferably, through a rod 34 in-

dicated by dotted lines, passing in a bore in the axis of the vertical shaft 8, the rod 34 being operated by a presser bar or the like 35, Fig. 1, by the operator, which presser bar 35 is the means for effecting the release of the lowermost type. 70

Upon the collar 33 on the vertical shaft 8 being so moved, the lever 32 in engagement therewith is rocked, and the opposite arm of the lever 32 will then be opposite 75 the first and second type control levers 25, 28 of the particular trough 5 of the font which is being dealt with, the operating lever 32 of the release device actuated by the sliding of the collar 33 acts upon the 80 second lever 28 of the type control device, and the projection 29 of the second lever 28 immediately grips that type which is next above the lowermost type, and this action simultaneously causes the first lever 25 to 85 rock about its fulcrum and to remove its tooth 27 from below the otherwise open end of that particular trough 5 of the font, and the lowermost type immediately slides into the composing stick 7 which is in position 90 beneath it.

The composing stick 7 having received its supply of type to compose a line, the said stick is then removed from its supporting devices on the vertical shaft 8 and 95 the line of type carried by said stick 7 is transferred to the type carrier as previously described. The stick is then replaced in its supporting devices on the vertical shaft of the machine to receive another line of type. 100

At Fig. 5 is shown a modified and it is considered a preferable construction of the devices for retaining and releasing the type in the font troughs 5, the similar parts at Fig. 5 being lettered to correspond with the 105 parts at Fig. 2, and these parts so similarly figured will consequently not require further description. Instead of the lever 32 directly acting upon the tail of the second lever 28 as at Fig. 2, the said lever 32 as at Fig. 5 carries a sliding plunger 32^x to act on the tail of the retaining lever 28. Beyond this the radial frame 14 is formed with a pair of teeth 14^x at a requisite distance apart, and the tail of the lever 28 is in such a position that when it is acted upon by the plunger 32^x it enters between the teeth 14^x and 110 positions and retains the radial frame 14 so that the composing stick 7 registers with the particular font trough 5 beneath which 115 it is located.

It should be understood that my invention is not strictly limited to the exact details of construction described but is as broad as is indicated by the accompanying claims. 120

125 What I claim is:

1. In type composing machines, the combination of a frame and a plurality of concentrically arranged type troughs arranged around the periphery thereof, a revoluble 130

- carrying device, a detachable composing stick carried thereby at a distance from the axis thereof, manually operated means for adjusting the position of said carrying means to position said stick in longitudinal alinement with and beneath any desired one of said troughs, and manually operated means for causing one type only to pass from the alined trough to said stick.
2. In type composing machines, the combination of a frame and a plurality of concentrically arranged type troughs arranged around the periphery thereof, a detachable composing stick, means for carrying the same, adapted to rotate to position said stick beneath any of said troughs, manually operated reciprocable keys corresponding to different types, and means operated different distances by said keys for adjusting the position of said carrying means to aline said stick with any desired one of said troughs.
3. In type composing machines, the combination of a frame and a plurality of type troughs arranged around the periphery thereof, open at their lower ends, a revolute shaft, coaxial with said font and extending below the same, a detachable composing stick carried by said shaft spaced apart therefrom in position to be alined with said type troughs, manually operated means for angularly adjusting said shaft about its axis to bring said stick beneath and in longitudinal alinement with any desired one of said troughs, means normally retaining the lowermost type in each of said troughs, and manually operated means for releasing the lowermost type and retaining the type immediately above the same in any one of said troughs with which said stick is alined.
4. In type composing machines, the combination of a frame and a plurality of type troughs arranged around the periphery thereof, a detachable composing stick, means for carrying the same, manually-operated keys corresponding to different types, means operated by said keys for adjusting the position of said carrying means to aline said stick with any desired one of said troughs, a presser bar, and means operated thereby for releasing one type only from the trough alined at any moment with said bar.
5. In type composing machines, the combination of a plurality of concentrically arranged type troughs, means for normally retaining the lowermost type in each of the same, a revolute carrying device, a detachable composing stick carried thereby, manually operable selective means, means actuated different distances thereby, to rotate said carrying device to bring said stick beneath any desired one of said troughs, an operating device, and means actuated thereby for releasing the lowermost type and retaining the type immediately above the

same in any one of said troughs with which 65 said stick is alined.

6. In type composing machines, the combination of a plurality of concentrically arranged type troughs, means for normally retaining the lowermost type in each of the 70 same, a revolute carrying device, a detachable composing stick carried thereby, manually operable selective means, means actuated different distances thereby, to rotate said carrying device to bring said stick 75 beneath any desired one of said troughs, a hand operated device, a member moved axially of said carrying device thereby, and means actuated by said member for releasing the lowermost type and retaining the 80 type immediately above the same in any one of said troughs with which said stick is alined.

7. In type composing machines, the combination of a plurality of concentrically arranged type troughs, a lever pivoted to each trough, having a projection arranged to normally retain the bottom type therein, a lever pivoted to each of said first levers, each having a projection and a tail, so arranged 85 that pressure on said tail will force said last named projection against the next uppermost type in the trough and oscillate said second lever about its said projection, to oscillate said first lever, through the pivotal 90 connection between said levers, to remove said first named projection from type retaining position, and manually operated means, arranged to be alined with the tail of any desired one of said second levers 95 100 and to operate the same.

8. In type composing machines, the combination of a plurality of concentrically arranged type troughs, members for normally retaining the bottom type in each trough, 105 members, normally out of operative position, for retaining the next uppermost type in each trough, a revolute member, selective means for revolving the same into alinement with any desired trough, said revolute 110 member being movable when thus alined, to operate said type retaining members and manually operable means for moving said revolute member to move the retaining member for the bottom type of the alined trough out of operative position and to move the retaining member for the next uppermost type of said trough into operative 115 position.

9. In type composing machines, the combination of a plurality of concentrically arranged type troughs, members for normally retaining the bottom type in each trough, members, normally out of operative position, for retaining the next uppermost type in 125 each trough, a revolute hollow shaft, coaxial with said type troughs, a detachable composing stick carried by said shaft, se-

lective means for angularly adjusting said shaft about its axis to bring said stick into alinement with, and beneath, any desired one of said troughs, a rod slideable in the bore 5 of said shaft, manually movable means for moving said rod, and means operated by the movement of said rod for moving the retaining member for the bottom type, of a

trough in alinement with said stick, out of operative position, and to move the retaining 10 member for the next uppermost type of said trough into operative position.

This specification signed and witnessed this 5th day of January, 1920.

WALTER CHIPPERFIELD.
